UNITED STATES PATENT OFFICE.

WILLIAM HUMANS, OF CAMBRIDGE, MASSACHUSETTS, ASSIGNOR TO THE AMERICAN MAGNETIC ELECTRIC COMPANY, OF JERSEY CITY, NEW JERSEY.

TELEPHONE.

SPECIFICATION forming part of Letters Patent No. 449,254, dated March 31, 1891.

Application filed July 23, 1885. Serial No. 172,434. (No model.)

To all whom it may concern:

Be it known that I, WILLIAM HUMANS, a citizen of the Dominion of Canada, residing at Cambridge, in the county of Middlesex and 5 State of Massachusetts, have invented a new and useful Magneto-Telephone, of which the following is a specification, reference being had to the accompanying drawings, making a part hereof, in which—

- 10 Figure 1 is a section on line $\alpha\alpha$ of Fig. 2, which is a plan with the diaphragm removed of one of my telephones, which can be used either as a transmitter or receiver. Fig. 3 is a detail, partly in section, illustrating the dia-
15 phragm and its clamping-bars. Fig. 4 is a sectional detail showing the spool and its coil and the projecting pole-piece for receiving the spool and containing the adjustable pole-
20 piece. Figs. 5 and 6 are diametrical sections at right angles one to the other of a telephone with a single pole. Fig. 7 is a plan of one pair of magnets, and Fig. 9 a bottom plan of the same. Figs. 8 and 10 are the top and bottom plans of the other pair of magnets. Fig. 25 11 is an edge view of one of the magnets. Figs. 12 and 13 are edge views of the two magnets, shown in plan, arranged together in Fig. 12 to form a telephone-case with two poles. Fig. 14 is a plan view showing the 30 telephone with four poles. Fig. 15 illustrates details, some of which are also illustrated in Figs. 15^a, 15^b, 15^c, 16, 17, and 18. Fig. 19 shows the telephone hung on a hook.

My invention is a telephone which consists, 35 essentially, of a compound permanent magnet consisting of at least two permanent magnets, each forming a portion of an annular or rectangular case, a diaphragm, and one or more pole-pieces, the free end of each pole-
40 piece being within the case and under the dia-
phragm.

The advantages of my invention are not only cheapness of construction and great durability, but also consist in concentration of 45 the magnetic field, so as to utilize the variations of that field to the fullest extent, not only to produce the movement of the dia-
phragm when my telephone is used as a re-

ceiver, but also to induce currents when used as a transmitter, and, moreover, the magnets 50 not only serve their function as magnets, but also act as clamps to hold the insulators or whatever else is to be clamped between them, and form a strong and durable casing or body, within which are the pole-pieces, coils, &c., 55 and upon which the diaphragm is secured.

In the drawings I have shown two pole-
pieces, each with its coil, and a diaphragm, which is divided by clamping-bars into two 60 semicircular diaphragms, one for each pole-
piece, and this is the second feature of my invention.

In the drawings, A A' A² A³ are four per-
manent magnets, each forming half a ring, so
that when put together they form a complete 65 ring or case with like pole to like pole.

Fig. 12 shows the magnets A' A² together, and Figs. 11 and 13 show the magnets A A³, which are placed upon the magnets A' A², and the four are held together by the hoop B 70 and cover G, as illustrated in Figs. 5 and 6. I prefer to form lugs a on the individual mag-
nets and to connect them by screws, as shown. Some of these screws also serve to hold the 75 pole-pieces a^2 a^3 in place, as clearly shown in Fig. 4.

A third feature of my construction consists in making the pole-piece tubular and insert-
ing a core in that tube, as shown in Fig. 4. This part of my construction relates to the 80 adjustment of the effective portion of the pole-piece, and in practice I make the tubu-
lar portion of the pole-piece a^3 as a nut, and the adjustable portion a^4 as a screw, so that by simply turning the pole-piece a^4 in the pole-
piece a^3 the nice adjustment requisite is read-
ily effected. The check-nut a^5 preserves the 85 adjustment.

The diaphragm D is shown clamped be-
tween two brass rings d d' , and the ring d is 90 secured to the magnets A A³, but the dia-
phragm may be itself clamped to the mag-
nets, although that will slightly reduce the
magnetic energy, if the diaphragm be of sheet-
iron, as it usually is. The rings d d' are 95 crossed by bars d^2 d^3 , which serve as clamps

to hold the diaphragm from moving when so clamped, thus practically forming two diaphragms, one for each pole-piece. Of course but one of the pole-pieces may be utilized, 5 and in that case the axis of the pole-piece will be in line with the center of the diaphragm and the cross-clamps d^2 d^3 dispensed with, and of course also four poles, or any other number, may be formed, and a pole-piece be used with all or any number of the poles, the diaphragm being clamped cross-wise, so as to make a suitable portion for each pole-piece used, as in Fig. 14.

The screw-cups shown in Figs. 16 and 17 15 are held in place by clamping the insulators ff' in recesses f^2 , formed to receive them in the magnets, all as clearly shown in Figs. 11, 12, 13, and 2. The hangers (shown in Figs. 15 and 15^a) and insulators (shown in Figs. 20 15^b and 15^c) are held in place in the same way in recesses f^4 . The hoop B is provided with holes to correspond with the holes formed by the recesses f^2 .

The pole-piece a^3 carries the coil a^6 , and 25 when two coils are used they are connected, as clearly shown in Fig. 2.

The bottom g is held in place by screws g' , as shown in Figs. 1 and 9, and the nuts g^2 are dropped in cavities g^3 , formed in the poles of 30 the magnets, as clearly shown in Figs. 1, 9, and 12, and the ring d is held on in the same manner, as clearly shown in Figs. 1, 6, and 7.

The cover G is held in place either by its closeness of fit or by small screws.

The holes in the bottom g are for adjustment of the additional pole-piece a^4 . 35

The cover G is of sheet metal struck up into the proper form for a telephone mouth-piece and may be held in place by the screws.

What I claim as my invention is— 40

1. A telephone consisting of a permanent magnet whose elements are connected pole to pole to form a case, a diaphragm extending across the open end of that magnetic case, and one or more pole-pieces and coils within 45 that magnetic case, all substantially as described.

2. In combination, the magnets recessed at f^2 , the insulator ff' , and means for holding the magnets together, whereby they act as 50 clamps for the insulators, all substantially as and for the purpose set forth.

3. In combination, the magnets $A A' A^2 A^3$, recessed at f^2 , and the hoop B, with the insulator f or f' or its equivalent, and means 55 for holding the magnets together, substantially as shown, whereby the magnets serve as clamps, as a case, and as magnets, all substantially as described.

4. The magnets $A A' A^2 A^3$, in combination 60 with the clamping-lugs a and pole-pieces a^3 , whereby the magnets are not only held together in pairs, but those pairs are also held together.

WILLIAM HUMANS.
